UNITED STATES PATENT OFFICE.

THOMAS A. LAMOTTE, OF PHILADELPHIA, PENNSYLVANIA.

DESIGN FOR A HOLDER FOR SHARPENING-TOOLS.

SPECIFICATION forming part of Design No. 26,257, dated November 10, 1896.

Application filed September 24, 1896. Serial No. 606,898. Term of patent 7 years.

To all whom it may concern:

Be it known that I, THOMAS A. LAMOTTE, a citizen of the United States, residing in Philadelphia, Pennsylvania, have invented a certain new and useful Design for a Holder for Skate-Sharpening Tools, of which the following is a specification.

My design for a holder for a skate-sharpening tool is fully illustrated in the accompanying drawing, the figure of which represents the holder in perspective.

The essential feature of the design is the holder having two parallel bars and a curved handhold.

; A A are two longitudinal bars connected together at each end by cross-bars a a, and extending from one cross-bar to the other above

the two longitudinal bars is a curved bar A', having rounded edges. The two bars A A form a channel c', and the bars A and curved bar A' form an opening c, which connects with the channel c'.

I claim—

The design for a holder of a skate-sharpening tool as herein described and as shown in the accompanying drawing.

In testimony whereof I have signed my name to this specification in the presence of two subscribing witnesses.

THOMAS A. LAMOTTE.
